UNITED STATES PATENT OFFICE.

LUCIEN G. LOCKE, OF PORTSMOUTH, OHIO.

TROUSERS HANGER, PRESS, AND STRETCHER.

1,111,476.

Specification of Letters Patent. Patented Sept. 22, 1914.

Application filed April 4, 1914. Serial No. 829,627.

To all whom it may concern:

Be it known that I, LUCIEN G. LOCKE, a citizen of the United States, residing at Portsmouth, in the county of Scioto and State of Ohio, have invented a new and useful Trousers Hanger, Press, and Stretcher, of which the following is a specification.

The present invention appertains to a trousers or garment hanger, press and stretcher, and aims to provide a novel and improved contrivance of that nature.

It is the object of the present invention to provide a device embodying a unique assemblage of component parts, whereby the same will be peculiarly adapted for both pressing and stretching one or more pairs of trousers.

Another object of the present invention is to provide an appliance of the character specified, which may be employed for stretching the trousers legs longitudinally as well as transversely or laterally, and for simultaneously pressing or creasing the trousers legs.

The present invention also comprehends the provision of a pressing and stretching device for trousers, which will be adjustable to accommodate various lengths and widths of trousers legs.

As a more specific object, the present invention contemplates the provision of a pair of opposite pressing devices, in combination with unique means for suspending the same, and for spreading or forcing the same apart, to stretch the trousers legs clamped by the pressing devices.

A further object of the present invention is to provide pressing devices embodying clamping or pressing bars, having unique means for clamping them together, or for liberating them when the trousers are to be inserted into or removed from the pressing devices. It is also within the scope of the present invention to provide a contrivance of the class specified, which will be comparatively simple, and inexpensive in construction, and which will be simple, convenient, practical, serviceable and efficacious in its use.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made

within the scope of what is claimed without departing from the spirit of the invention.

The invention has been illustrated in its preferred embodiment in the accompanying drawing, wherein:

Figure 1 is a front elevation of the improved device, portions being broken away. Fig. 2 is an enlarged cross sectional detail taken on the line 2-2 of Fig. 1. Fig. 3 is an elevation of the parts depicted in Fig. 2, on an enlarged scale. Fig. 4 is a fragmental perspective detail of one extensible link.

In carrying out the present invention there is employed a pair of opposite pressing devices 1, each of which embodies a pair of clamping or pressing bars 2, which are preferably, although not necessarily, constructed of wood.

In order to connect the pressing devices 1, those clamping or pressing bars 2, which are at the remote or far side in Fig. 1 and which will be denominated the rear bars, are provided in their inner edges and adjacent their upper and lower ends, with recesses or sockets 3, the upper and lower recesses 3 of the rear clamping bars 2 complementing each other and being in alinement. Upper and lower extensible links 4, each comprising a pair of overlapping sections or rods 4^a have their remote ends provided with eyes pivoted within the upper and lower recesses 3, respectively, by means of screws or other pivot members 5 engaged into the rear bars 2 through the recesses 3. The sections or rods 4^a of the links 4 are provided at their inner ends with loops 6 embracing the opposite sections or rods, whereby the sections or rods may expand or contract longitudinally to render the link extensible. It will thus be observed that the links loosely connect the upper and lower ends of the pressing devices to be shifted to and from each other, or to be angled more or less with respect to one another, to accommodate various trousers legs.

In order to suspend or support the pressing devices and for conveniently separating or spreading the pressing device, the rear clamping bars 2 are provided in their inner edges, and intermediate their ends with recesses 7 in which are pivoted the remote or outer ends of a pair of toggle links 8 which are provided at their inner or adjacent ends with apertures 9, an upright hanger or suspension rod 10 having its lower end engaged to certain apertures of the two links

or levers 8, and provided with an eyelet or loop 11 at its upper end for engaging a nail, hook or other supporting element for suspending the entire structure. The toggle links 8 converge downwardly, from the pressing devices 1, whereby when the pressing devices 1 are suspended through the medium of the rod or stem 10, there will be a tendency to spread or separate the pressing devices, due to the tendency of the toggle links to aline under the weight of the pressing devices.

In order that a coat, vest, or other garment may be supported by or hung from the present contrivance, a coat or garment hanger 12, of any suitable make, is secured to the upper end portion of the rod or stem 10, in order that one or more coats or other garments may be applied to the hanger 12 over the upper ends of the presses or pressing devices 1 in a convenient manner.

For the purpose of clamping the clamping or pressing bars 2 of each press 1 together, the said bars of each press 1 are provided with upper and lower clamping devices 13 adjacent the ends of the bars 2 or the links 4. Each clamping device 13 embodies a pair of links or levers 14 having certain ends pivoted or fulcrumed to the angular ears of brackets 15 secured to the remote or outer sides or faces of the respective bars 2, the other end portions of the levers or links 14 being curved as at 16, so as to converge or meet, and the last mentioned ends of the links or levers 14 being pivoted or fulcrumed together as at 17. It will thus be obvious, that the pressing or clamping bars 2 of each press 1, being connected by the upper and lower links 14 as above described, will permit the bars 2 to be readily swung apart or swung together, as desired, when the links 14 are free. The links 14 of the two presses project outwardly or away from each other, so as not to encumber the space between the two presses or pressing devices, and to enable the front or forward bars 2 to be swung open away from the rear bars.

Each of the clamping devices 13 is provided with means for drawing the links or lever 14 toward each other, when the respective pressing or clamping bars 2 are swung together, and to this end, a U-shaped latch and draft member 18 has its bend or intermediate portion pivoted through one of the links or levers 14 intermediate its ends and is arranged to swing astride the other link or lever 14. The latch 18 is preferably pivoted or fulcrumed to that link or lever 14, pivoted to the rear bar 2, whereby the arms or ends of the latch 18 will project forwardly when they are swung over the forward link or lever 14. A saddle 19 is arranged to straddle one of the levers or links 14 and is provided at its ends with

outturned apertured ears 20 slidably engaging the respective arms or limbs of the latch 18, whereby when the latch 18 is swung over the forward link or lever 14, the saddle will engage the outer or forward edge of the said lever or link. The saddle 19 is provided at its intermediate or crotch portion with the lateral apertured ear 21 loosely engaging or embracing one of the arms of the latch 18, a thumb nut 22 being threaded upon the said arm of the latch to seat against the ear or bearing portion 21 of the saddle, a washer 23 being preferably interposed between the nut 22 and the ear 21. When the latch 18 is swung over the forward link or lever 14, and when the nut 22 is tightened, the saddle 19 will engage the said link or lever 14, and as a consequence, the two links or levers 14 will be drawn toward each other, to tightly clamp the bars 2 together, for pressing the trousers legs therebetween.

In use, to place a pair of trousers in the presses 1, the same are preferably laid upon a table or other surface, with the back or rear bars lowermost. Then, by unscrewing the nuts 22 slightly, the latches 18 will be released, and may be swung out of engagement with the upper or forward links or levers 14, in which event, the forward or upper bars 2 may be swung open. The back or bottom bars 2 are readily adjusted to and from each other, to accommodate the width of the trousers legs properly, and the trousers may then be placed upon the lower bars 2 with the creased portions resting directly upon the said bars. The upper bars, or those bars 2 which are previously swung open, may then be swung to closed position, over the creased portions of the trousers legs. The clamps 13 at one end are tightened by swinging the latches over the proper links or levers 14, and by tightening the nuts 22 whereby one end of the trousers legs are clamped between the corresponding ends of the two presses 1. The operator may then pull the other ends of the trousers so as to stretch them longitudinally, and after the trousers legs have been stretched longitudinally, the other clamps 13 may be tightened, as above intimated, to clamp the other ends of the pressing bars 2 together, whereby the creased portions of the trousers will be clamped throughout their lengths between the two pair of clamping or pressing bars 2. The presses 1 are then suspended from a nail, hook, or other supporting means, through the medium of the suspending rod which will cause the presses 1 to have a spreading or separating action, due to their tendency to gravitate and swing with the toggle links or levers 8. The weight of the presses and trousers thus creates a transverse tension upon the trousers legs, which will serve to stretch the same in order to remove wrinkles or false creases. The

stretching action will thus be rendered automatic, the tension being applied to the trousers legs, as long as the device is suspended by the rod 10.

- 5 The trousers may be removed readily by opening the clamping bars 2 of the presses, after the latches 18 are liberated, as will be clearly obvious from the foregoing without further comment. A number of pairs of 10 trousers may be pressed and stretched simultaneously, with the present contrivance, and to the hanger, to be suspended conveniently one or more other garments may be applied over the trousers. The present device thus 15 provides a combination suit hanger and trousers press of considerable utility.

From the foregoing, taken in connection with the drawings, the other advantages and capabilities of the present device will be obvious without the necessity of extensive description, it being noted that the objects aimed at have been carried out satisfactorily by the provision of the structure herein disclosed.

25 Having thus described the invention, what is claimed as new is:—

1. A garment press comprising a pair of clamping bars, and clamps for the said bars, each clamp embodying a pair of pivoted levers connected to the remote sides of the bars, and a latch pivoted to one lever intermediate its ends and adapted to swing into and out of engagement with the other lever.

2. A garment press comprising a pair of 35 clamping bars, and clamps for the said bars, each clamp embodying a pair of pivoted levers connected to the remote sides of the bars, a latch pivoted to one lever intermediate the ends thereof and adapted to swing into and out of engagement with the other lever, and an adjustable member carried by the latch and engageable with the last mentioned lever for swinging the levers toward one another.

40 45 3. A garment press comprising a pair of

clamping bars, and clamps for the said bars, each clamp embodying a pair of pivoted levers connected to the remote sides of the bars, a latch pivoted to one lever intermediate its ends, a saddle slidable upon the latch and engageable with the other lever, and a nut threaded upon the latch and coöperable with the saddle.

50 4. A garment press comprising a pair of clamping bars, and clamps for the said bars, each clamp embodying a pair of pivoted levers connected to the remote sides of the bars, a U-shaped latch pivoted to one lever, a saddle slidably engaging the arms of the latch and engageable over the other lever, and means for adjusting the saddle along the latch.

55 5. A garment press comprising a pair of clamping bars, and clamps for the said bars, each clamp embodying a pair of pivoted levers connected to the remote sides of the bars, a U-shaped latch having its intermediate portion pivoted through one of the levers, a saddle having angular apertured ears 60 65 slidable upon the arms of the latch, the saddle being adapted to straddle the other lever, and a nut threaded upon one arm of the latch and coöperating with the saddle.

6. In a garment press, a pair of clamping bars, and clamping devices therefor, each 70 75 embodying a pair of levers connected at certain ends to the remote sides of the bars, the other end portions of the levers being curved and pivoted together, a latch pivoted to one lever intermediate its ends, and an adjustable saddle carried by the latch and engageable with the other lever.

In testimony that I claim the foregoing as my own, I have hereto affixed my signature in the presence of two witnesses.
